UNITED STATES PATENT OFFICE.

GUSTAV A. LANDENBERGER, OF PHILADELPHIA, PENNSYLVANIA.

STOP-MOTION FOR KNITTING-MACHINES.

SPECIFICATION forming part of Letters Patent No. 760,998, dated May 24, 1904.

Application filed December 22, 1903. Serial No. 186,173. (No model.)

To all whom it may concern:

Be it known that I, GUSTAV A. LANDENBERGER, a subject of the Emperor of Austria-Hungary, (having resided in the United States 5 one year last past and having declared my intention to become a citizen of the United States,) residing at Philadelphia, in the county of Philadelphia and State of Pennsylvania, have invented a new and useful Improvement 10 in Stop-Motions for Knitting-Machines, of which the following is a specification.

My invention relates to stop-motions for knitting-machines.

It consists of novel means operative in case 15 of a tight cop, a knot in the yarn, or a break therein for throwing off the power from the machine and for quickly arresting its motion.

It further consists of other novel features 20 of construction, all as will be hereinafter fully set forth.

Figure 1 represents an elevation of so much of a knitting-machine as is necessary to show my invention. Fig. 2 represents a similar elevation taken at a right angle to that shown 25 in Fig. 1. Fig. 3 represents a horizontal section through the line α α , Fig. 2. Figs. 4 and 5 represent fragmentary details of the stopping device.

Similar numerals of reference indicate 30 responding parts in the figures.

Referring to the drawings, 1 designates the driving-shaft of a knitting-machine having fast and loose pulleys 2 and 3. From the shaft 1 are driven all the working parts of the machine shown and not shown in the drawings. 35 4 designates the base or stand of the machine, from which rises the usual rod 5, adapted to carry the stop-motion devices. Secured on the rod 5 is a bracket 6, carrying a block 7, 40 on which is pivoted a lever 8. At the outer end of the lever 8 is a fork 9. The bracket 6 also carries a block 10, on which is pivotally supported a bent rod 11, carrying a weight 12. On the rod 11 are laterally-projecting 45 pins 13. A stop 14 limits the rearward motion of the rod 11. Supported on the upright 5 are bars 15, in which is guided a rod 16, resiliently supported by means of a spring 17 on a cross-bar 18 at the top of the rod 5. The

rod 16 is provided with a fork 19 at its upper 50 end. Secured to the cross-bar 18 is a tension-spring 20, having at its free end a hook 21. Apertures 22 and 23 at the ends of the cross-bar 18 are adapted to receive the yarn 24, as clearly shown in Fig. 1. Pivoted on the upright 5 are levers 25 and 26, connected by a vertical rod 27. The free end of the lever 25 is provided with a plate 28. (Shown in Figs. 1 and 2.) From the free end of the lever 26 depends a rod 29, resiliently supported by a 60 light spring 30. The rod 29 is shown passing through the base 4 of the machine and has pivoted at its lower end a lever 31, the length of which is adjustable by means of a turnbuckle 32. Supported in a bracket 33 65 beneath the stand 4 is a rod 34, connected by a pitman 35 with the lever 31. The rod 34 is forced in the direction of its free end by a spring 36. As shown in Fig. 3, the end 37 of the rod 34 engages with a block 38 on a shaft 70 39, longitudinally actuated by a spring 40 and carrying forks 41, adapted to engage with a belt 42, and a brake 43, adapted to bear against the web of the fast pulley 2. On the shaft 1 is mounted a small pulley 44, from which a 75 belt 45 runs to a wheel 46, having a plurality of teeth 47 and supported, as shown in Fig. 1, on a leg 48 of the standard 4.

The operation is as follows: The thread 24 from the cop 49 is carried upward through a 80 suitable guide 50, which leads it through the fork 9 on the lever 8, thence upward through the aperture 22 in the rod 18, over the fork 19 of the rod 16 and hook 21 of the tension-spring 20, and thence through the aperture 23 85 at the other end of the rod 18 to the needles, its path being shown in Figs. 1 and 4. The thread in passing over the fork 29 to the aperture 22 bears against the pins 13 of the lever 11 and prevents the lever from falling. In 90 case of what is known as a "tight" cop—that is, where the yarn 24 does not readily slip off the cop or bobbin 49—the strain on the thread will be communicated through the rod 16 to the plate 28 on the lever 25. This will tend to depress the free end of the lever 25, which, acting through the rod 27, lever 26, and rod 30, will depress the lever 31, so that its point 95

will engage with one of the teeth 47 of the wheel 46. The effect of this will be to swing the lever 31 to the left of the drawing Fig. 1, so that the dog 37 will be withdrawn from contact with the block 38 on the shaft 39. The heavy thrust-spring 40 will then act to positively move the rod 39 to the right of Figs. 2 and 3, thus shifting the belt 42 from the fixed pulley 2 to the loose pulley 3 and at the same time applying a shoe of the brake 43 to the web of the pulley 2, thus both cutting off the power from the machine and positively braking its motion. In the event of a knot, as 51, (shown in Fig. 1,) occurring in the thread 24 10 the same will engage with the fork 9 on the lever 8 and through the connection of the free end of that lever with the plate 28 depress the plate, with the result just described.

Should the thread 24 break or come to an 20 end, the weighted lever 11 being no longer supported by the contact of the thread with the pins 13 will fall forward, as shown in dotted lines, Fig. 1, and strike the lever 25, so as to depress the same and, as before, cut off 25 the power and stop the motion of the machine.

It will be seen that my device provides efficient means for promptly stopping the machine in case of any one of the three accidents to the yarn to which knitting-machines are 30 subject and that all these means act through a single mechanism, beginning at the plate 28 and continuing to the shifter and brake device.

It is evident that various changes may be made by those skilled in the art which will 35 come within the scope of my invention, and I do not, therefore, desire to be limited in every instance to the exact construction herein shown and described.

Having thus described my invention, what 40 I claim as new, and desire to secure by Letters Patent, is—

1. A stop-motion for a knitting-machine comprising positively-actuated power-arresting means, means for releasing the same including a continuously-rotated wheel, a lever engageable therewith and means for forcing such lever into engagement with said wheel, and a weighted portion normally sustained by the yarn and adapted to percussive engage-

ment with said lever-engaging means in the event of a break or termination of the yarn.

2. A stop-motion for a knitting-machine comprising positively-actuated power-arresting means, means for releasing the same including a continuously-rotated wheel, a lever engageable therewith and means for forcing such lever into engagement with said wheel, and means for normally deflecting the yarn from its path, said deflecting means being operatively engageable with said lever-engaging means in the event of an increased strain on the yarn.

3. A stop-motion for a knitting-machine comprising positively-actuated power-arresting means, means for releasing the same including a continuously-rotated wheel, a lever engageable therewith and means for forcing said lever into engagement with said wheel, a weighted portion normally sustained by the yarn and a movable portion normally deflecting said yarn from its path, both said weighted portion and said deflecting means being alternately engageable with said lever-engaging means.

4. In a stop-motion for a knitting-machine, 75 positively-actuated power-arresting means, means for releasing same including a continuously-rotated wheel, a lever engageable with said wheel and a pivoted weighted portion adapted to be sustained by the yarn and to 80 have percussive engagement with means for moving said lever into engagement with said wheel in the event of a break or termination of the yarn.

5. In a stop-motion for a knitting-machine, 85 positively-actuated power-arresting means, means for releasing same including a continuously-rotated wheel, a lever engageable with said wheel and a longitudinally-movable rod by which the yarn is carried out of its straight 90 path, said rod being operatively connected with means for moving said lever into engagement with said wheel.
